ELECTRON DISCHARGE DEVICE AND
METHOD OF MANUFACTUREWilliam C. Dale, Livingston, N. J., assignor to
Radio Corporation of America, a corporation
of Delaware

Application November 26, 1946, Serial No. 712,267

5 Claims. (Cl. 250—27.5)

1

My invention relates to electron tubes, and more particularly to such tubes in which the electron stream is required to traverse at least two grid members, and to their manufacture.

The employment of a plurality of grids in electron tubes between the cathode and anode is associated with difficulties which must be overcome in order to prevent impairment of tube characteristics. Thus in tetrodes, for example, where a screen grid is interposed between the anode and control grid, there is a tendency for the electrons emanating from the cathode to be absorbed by such screen grid and produce undesired current therein.

It has heretofore been recognized that the most effective way to shield certain grids in an electron tube from primary electrons is to align the grid closest to the cathode, such as the control grid, which is usually biased slightly negative with respect to the cathode, with the turns of the other grid or grids following the control grid. To accomplish such alignment it has been the practice to first mount one grid upon its support and then mount the other grid or grids upon their supports, after first manually adjusting their longitudinal positions so that their turns are in line in the direction of the electron travel from the cathode to the anode. However, such manual adjustment is not entirely satisfactory for the reasons, among others, that it involves an undesirable time expenditure and is dependent upon the operator's faculties which may not always be reliable. The lack of reliability of such manual adjustment is more pronounced in the manufacture of small sized tubes where the parts are comparatively small and require a more or less precise positioning.

It is, accordingly, the principal object of my invention to minimize absorption of electrons by one or more of a plurality of grids in an electron tube, where such absorption would result in impairment of tube characteristics.

It is a more particular object of my invention to align the transverse grid wires of a plurality of grids in an electron tube in directions normal to the cathode, in an accurate manner and with a saving of time.

A further object of my invention is to support a plurality of grid members in an electron tube in such a manner that the support is accomplished

2

only when the grid members are in a predetermined longitudinal position required for alignment of their transverse grid wires in directions normal to the tube axis.

5 Further objects of my invention will suggest themselves as the description proceeds.

While the scope of my invention is pointed out particularly in the appended claims, it may best be understood from the following detailed description of an embodiment thereof, taken in connection with the accompanying drawing, in which

10 Figure 1 shows an elevation partly in section of an electron tube having two grids made in accordance with my invention with the turns thereof automatically aligned in assembly;

15 Figure 2 shows an elevation of one of the grids employed in the tube illustrated in Figure 1;

20 Figure 3 shows an elevation of the other of said grids which has larger lateral dimensions than the grid of Figure 2, permitting it to be placed over and surround said grid in coaxial relationship and at a predetermined distance therefrom;

25 Figures 4, 5, 6 and 7 show one way of making the grids illustrated in the previous figures; Figure 4 showing the cutting of the rods to suitable length; Figure 5 depicting the manner in which lateral extensions or swages are provided on the rods; Figure 6 illustrating the completed rod; and Figure 7 showing the step of applying transverse grid wires to two of such rods and clearly indicating the function of the swages in determining the longitudinal position on the rods of the first transverse grid wire.

30 Referring now to Figure 1, there is shown an electron tube having an envelope 10 enclosing an electrode mount including cathode 11, flattened elliptical anode 12, shown in cross section, two grids 13, 14 and two insulating spacers 15, 16

35 between which the electrodes are supported. The tube is also provided with external contact pins 17. Grid 13 has a pair of grid side rods 19 and grid 14 includes grid side rods 20. Grids 13, 14 are shown in Figures 1, 2 and 3 as having an accentuated linear pitch for purposes of illustration.

40 In accordance with my invention grid side rods 19, 20 are provided with swages 18, each of which is provided with an upper and lower surface as viewed in Figure 1, normal to the side rods. The

first turn on each of grids 13 and 14 is applied to one of each pair of said side rods 19, 20 beginning at a portion thereof longitudinally spaced a predetermined distance X from the lower surfaces of swages 18. The grid-wire-turns on each of the grids referred to start at a common side of cathode 11 as shown in Figure 1 and observe a corresponding linear pitch. The lower surface of each of swages 18 abuts against the upper surface of insulating spacer 16. Since this surface of spacer 16 is planar the lower surfaces of swages 18 lie in a common plane. Since the distance X represents longitudinal spacing of the point of beginning of the grid-turns on each of grids 13, 14 from the lower surfaces of swages 18, these points of beginning of said grid turns lie in a common plane. Since the turns of each grid are characterized by a corresponding linear pitch it follows that when grids 13, 14 are mounted in such a manner that the lower surfaces of swages 18 abut the upper surface of spacer 16, the grid turns of one of the grids are in line with the grid turns of the other grid substantially in planes parallel to the direction of the electron flow from the cathode to the anode.

The alignment of the turns of one grid with the turns of one or more other grids in a common device is achieved according to my invention to the extent that inherent possibilities for such alignment exist in a given structure. When planar grids are involved, which are rectilinearly displaced, an actual alignment of the turns thereof in planes parallel to the direction of electron travel is accomplished. However when the grids are circular or elliptical or of flattened elliptical cross section and are concentrically disposed actual alignment of the turns of several such grids throughout their lengths is inherently impossible unless special recourses are availed of such as modifying the pitch of the turns in some of the grids in proximity to the grid side rods to balance the variation that such structure tends to produce in the grid turns of several grids. However, while my invention as applied to circular or elliptical grids results in a crossing of the grid turns of one grid by the grid turns of another grid, such crossing takes place substantially midway between the two side rods where the value of the electron stream is at a maximum. The crossed turns describe sharp angles as they diverge toward the side rods, such divergence being relatively slight and being at a minimum where alignment of the turns is most needed and at a maximum where such alignment is less significant. For shielding purposes, therefore, the alignment produced by my invention is effective for grids of any type.

In carrying out my invention any desired number of grids for use in a common tube are first prepared. Figures 2 and 3 show two of such grids having cross sections of such shape that the narrower grid of Figure 2 is adapted to be received within the wider grid of Figure 3. Although for purposes of illustration grids of such cross sectional area to permit concentric relationship therebetween are described herein, it will be understood that my invention is equally well adapted for use in connection with planar grids or grids of any cross sectional shape which employ side rods for supporting the grid turns. As shown in Figures 2 and 3 notwithstanding the difference in cross section normal to the longitudinal axis between the grids, the longitudinal displacement along the side rods of the point of beginning of the first grid turn from the lower

surfaces 21 of the swages 18, is represented by a similar value X for each of the grids. Moreover the linear pitch of the turns of grid 13 corresponds to the linear pitch of the turns of grid 14. This linear pitch may be uniform as shown in Figures 2 and 3. It may also be non-uniform as for variable mu applications. However, such non-uniformity of linear pitch must correspond in each of the grids, the turns of which are to be aligned.

As will be apparent from the foregoing, an important element in my invention is the provision of swages 18 which provide a convenient datum means for determining the location longitudinally on the rods of the start of the first grid turn thereon. In the instant embodiment of my invention a plurality of similar grid side rods, one of which is shown in Figure 6, are prepared as shown in Figures 4 and 5. Use is made of two cutting means 33, 34 shown in Figure 4 suitably spaced from each other by a bar 35. This permits the successive cutting of a plurality of rods having equal lengths. The cut rods are next subjected to a swaging operation shown in Figure 5. This may be accomplished by square ended members 36, 37 suitably spaced by rod 38. Instead of two swages, one swage may be applied to each rod without impairing its usefulness in carrying out the purposes of the invention. During the swaging step the rod is held against movement by members 39, 40 and is pressed by members 36, 37, by actuating means not shown, against anvils 41, 42 which are each provided with a rectangular recess having a length greater than the diameter of the rod and a width substantially equal to that of one of said members 36, 37.

Although the steps of cutting and swaging the side rods shown in Figures 4 and 5 result in identical dimensioned grid side rods, this similarity of the rods is not essential for operativeness of the invention. For example, the rods may be of unequal length and the swages may be applied at differently spaced longitudinal locations on several rods. The only critical dimensional requirement of the rods is that they possess a length from the lower surface 21 on swages 18 to the far ends of the rods sufficient for bridging the axial displacement of the insulating spacers 16 and 17 shown in Figure 1 and for support by said spacers.

The grids shown in Figures 2 and 3 owe their property of automatic alignment when mounted in a device such as is illustrated in Figure 1, to the novel structure thereof according to the invention. As shown in Figure 7, this structure permits the step of winding a grid wire on the previously prepared grid side rods to provide each of the grids depicted in Figures 2 and 3. Side rods 19 are supported in fixed spaced relationship by chucks 22, 23 which are provided with suitable recesses for receiving the ends of the rods. Chucks 22, 23 may each be provided with two or more pairs of such recesses for accommodating grid rods successively in a plurality of different spaced relationships for a plurality of chucks of cross-sectioned grids or a plurality of chucks of the character of 22, 23 may be used, each having a pair of recesses differently spaced. The ends 19 are so positioned that swages 18 thereon abut planar surface 24 of chuck 22. Chucks 22 and 23 are so disposed that they hold rod 19 perpendicular to the planar surface 24. Although additional swages 25 are shown on rods 19 at the ends thereof remote from the ends on which swages 18 are applied, such additional swages may be omitted without departing from the invention.

Two side rods thus supported provide a fixed frame on which grid wire may be wound. The grid winding step may involve the use of a notching wheel 26 for cutting a transverse groove in side rods 19. Grid wire is threaded into said groove from a suitable wire source (not shown). Peening wheel 27 is then brought into operative position to close the groove referred to to embed a transverse portion of the wire therein. To permit this wire winding procedure, the chucks may be rotatable and the notching and peening wheels 26 and 27 may be supported on fixed supports, or the chucks may be fixed and the wheels referred to may rotate around the rods 19.

Notching wheel 26 is supported on a structure which includes arm 28, and peening wheel 27 is associated with an arm 29. Arms 28 and 29 are provided with a critical length from their free ends to adjacent surfaces of wheels 26 and 27. The arms are also provided with planar end surfaces 30, 31 normal to their longitudinal axis. In operation surfaces 30, 31 of arms 28, 29 abut against a portion of the planar surface 24 of chuck 22. Therefore at the beginning of a grid winding operation wheels 26, 27 are spaced a predetermined distance from surface 24. The first turn of grid wire on rods 19 is, therefore, begun at a point on one of the rods which is displaced normally from surface 24 and consequently from surface 21 on swaging member 18, a predetermined distance. The grid winding operation may be continued in known manner until the grid is completed.

It will be apparent from the foregoing that my invention provides an accurate and automatic alignment of the grid turns of a multi-grid structure and eliminates the necessity for manual adjustments. It, therefore, accomplishes a saving in time in the manufacture of a device employing the grid structure referred to, permitting a reduction in cost while enhancing the operative efficiency of the device.

While I have chosen one embodiment for the purpose of illustrating my invention, it is to be distinctly understood that my invention is not limited thereto. Various modifications may be made in the embodiment described without departing from my invention. For example my invention may be employed in connection with grids each having only one supporting side rod. I desire to include these and other modifications as may suggest themselves to persons skilled in the art within the scope of the appended claims.

What I claim as new is:

1. An electron tube having a cathode, an anode substantially co-extensive with said cathode, and at least two wound grids disposed between and parallel to said cathode and anode, said grids comprising side rods supporting a plurality of turns of grid wire, two spaced parallel insulating plates for supporting said side rods, and uniform lateral projections on said side rods forming planar surfaces normal to said side rods, like planar surfaces on said rods being spaced equally from the first turn of grid wire on each grid, the corresponding grid turns on each of said grids having a corresponding linear pitch and said like planar surfaces abutting against a common surface of one of said plates, whereby the turns of one grid are accurately aligned with the turns of the other of said grids in planes normal to the cathode and anode and parallel to the direction of electron travel in said tube.

2. An electron tube having electrodes including a plurality of grids, said grids including side rods,

and at least one insulating plate for supporting one end of said side rods, at least one lateral projection on each of said side rods having a planar surface normal to said rods engaging a common surface of said plate, the corresponding transverse grid wires on each of said grids having correspondingly linear displacement along said rods, said planar surface being spaced a predetermined distance from the first of said transverse grid wires, whereby the grid wires on one grid are effectively in line with the grid wires on another of said grids in predetermined planes, for effective shielding of at least one of said grids by another of said grids.

15 3. An electron tube having at least a cathode, an anode and two grids, each of said grids including at least one side rod for supporting grid wires thereon, said grid wires being similarly spaced on said grids, like planar means on each of said at least one side rod equally spaced from the first of said grid wires, and said planar means comprising a swage on said side rod having a planar surface normal to said rod, additional planar means for supporting said rods with said like planar means thereon in the same plane and adjacent each other, whereby the grid wires of one of said grids are effectively in line with corresponding grid wires of the other of said grids in planes parallel to the direction of electron travel from said cathode to said anode.

20 4. An electron tube having at least a cathode, an anode, and two grids, said grids having side rods for supporting a grid wire thereon, lateral projections on said side rods forming planar surfaces normal to said side rods, said grid wire extending transversely and longitudinally of said side rods and being fixed thereto, the magnitude of longitudinal extension of said grid wire towards one end of said rods being determined by certain of said planar surfaces, the longitudinal pattern of said grid wire in one of said grids being similar to the longitudinal pattern of said grid wire in the other of said grids, and means for supporting said grids with said certain of said surfaces in a common plane and adjacent each other, whereby one of said grids effectively shields the other of said grids from electrons flowing from the cathode to the anode.

25 5. An electron tube having a cathode, an anode, at least two grids, and at least one insulating plate for supporting said grids, each of said grids having parallel transverse portions of corresponding longitudinal displacement, stop means on said grids having a planar surface normal to the longitudinal axes of said grids and engaging a common surface of said plate, the first of said parallel transverse portions on each of said grids being similarly spaced from said planar surface of said stop means, whereby the parallel transverse portions of one of said grids are effectively in line with the parallel transverse portions of the other of said grids in planes parallel to the direction of travel of electrons from said cathode to said anode.
